UNITED STATES PATENT OFFICE.

ADOLF KROETER, OF ST. LOUIS, MISSOURI.

DESIGN FOR A COOKING-PAN.

SPECIFICATION forming part of Design No. 23,930, dated January 1, 1895.

Application filed December 10, 1894. Serial No. 531,422. Term of patent 7 years.

To all whom it may concern:

Be it known that I, ADOLF KROETER, of the city of St. Louis, State of Missouri, have invented a new and original Design for a Cooking-Pan, of which the following is a full, clear, and exact description, reference being had to the accompanying drawings, forming a part hereof.

In the drawings: Figure 1 is a top plan view of a cooking-pan of my design. Fig. 2 is a sectional view taken approximately on the indicated line 2—2 of Fig. 1.

The leading feature of my design consists of a circular plate provided with a series of radially arranged depressions, the same being uniform in size and occupying the same horizontal plane.

1 indicates the plate, the same being circular in form and provided with an integral

flange 2, the same extending upwardly and outwardly from the periphery of the plate 1. Oppositely arranged upon the upper edge of this flange 2 are integral rectangular projections 3, the same extending upwardly and outwardly from the edge of the flange 2.

4, 4 indicate depressions radially arranged in the body of the plate 1, said depressions being approximately semi-circular in cross-section.

What I claim is—

The design for a cooking-pan, as herein shown and described.

In testimony whereof I affix my signature in presence of two witnesses.

ADOLF KROETER.

Witnesses:

W. C. HOWLAND,
JNO. C. HIGDON.
